UNITED STATES PATENT OFFICE

2,412,183

READING AND WRITING MACHINE

Walter P. Taylor, Jr., New York, N. Y.

Application July 7, 1942, Serial No. 450,079

5 Claims. (Cl. 197—6.1)

1

The invention relates to apparatus for embossing characters so as to be readable by touch and to devices for translating such characters into sound, as well as to tapes embossed with such characters. It is particularly intended for use by blind persons.

The usual type of matter intended to be read by the blind is the well-known Braille. This, however, is somewhat complicated, and machines for writing it are very complex.

The primary object of the present invention is to provide a simplified system for use by the blind. More especially, it contemplates the use of a simple code composed of two types of symbols, such as the common Morse code.

A second object of the invention is to provide a simple and effective device for embossing such symbols on a tape or the like, particularly a device utilizing only two keys and a spacing member. It includes an arrangement by which both symbols are in the same line longitudinally of the tape, at least in part, so that the fingers of a reader moving along the tape need follow only this line to detect all of the symbols. The danger of missing some of the symbols is thus greatly reduced, and the ease and accuracy of reading are increased.

In this respect, the invention contemplates the use of two members arranged side by side in the direction of movement of the tape, with a mechanism for causing such members to emboss the successive symbols at proper intervals.

An additional object of the invention, in connection with such an embossing mechanism, is the arrangement of the tape feeding mechanism in such a way as to clear the embossing at each stroke of the machine, this being preferably accomplished by arranging rollers on opposite side of and above the embossing anvil.

The invention further includes a device for reading a tape so printed. One object of this device is to provide an audible tone of differing sound for each type of symbol, so that the listener can easily follow the message on the tape as it is fed through.

A further object of this device is to prevent the transmission of impulses to the sound emitting apparatus by creases or seams in the tape.

Still another object is to provide, in connection with the type of tape described above, having parts of all symbols in the same line longitudinally of the tape, parts actuated by projections in different horizontal lines, one of which is actuated by all the symbols and the other by only one type of symbol; with such an arrange-

2

ment that the actuation of one part only produces one sound tone while the actuation of both produces a distinguishable sound tone.

Another feature of the invention resides in the completed tape itself, which has been described above.

Further objects and advantages of this invention will be apparent from the accompanying drawings which form a part thereof.

10 In the drawings:

Fig. 1 shows in side elevation with parts broken away an embossing device according to one embodiment of my invention;

15 Figs. 2 and 3 are cross sections generally along the lines 2—2 and 3—3 of Fig. 1;

Fig. 4 is a detail of the spacing mechanism;

Figs. 5 and 6 show two types of tape embossed in accordance with the invention;

20 Fig. 7 is an end view of a reading device according to the invention;

Fig. 8 is a cross section on the line 8—8 of Fig. 7; and

Fig. 9 is a top plan view thereof.

The embossing mechanism includes a frame

25 2. At the ends of the frame are blocks provided with guide channels 4 for a paper strip on which the embossing is to be done. Between these channels the paper passes over idling guide roller 6 and between guide roller 8 and driving rollers

30 10. Between these two sets of rolls the paper passes above an anvil 12 having thereon dies or impression blocks 14, 16 for the two types of symbols. Preferably, as shown in Fig. 5, these are dots and dashes, with the dashes running transversely of the strip, but partly in the same line longitudinally of the strip as the dots.

The movable printing members are rods 18, 20 having recesses mating with the projections of dies 14 and 16. These rods are pivoted at

40 22 to guide links 24 which are pivoted at 26 to the machine frame. They are also pivoted at 28, 30 to levers 32, 34, respectively. These levers are mounted to turn freely on a rotatable shaft 36. Pawls 38, 40 on the two levers engageable

45 with ratchets 42, 44 rigid with shaft 36 cause the shaft to turn counterclockwise (Fig. 1) whenever one of the levers turns counterclockwise, but allow the shaft to remain stationary when the levers turn clockwise.

50 Rigid on shaft 36 is a pinion 46 which meshes with a pinion 48 connected to paper driving roller 10, so as to move the paper to the left (Fig. 1) when the shaft 36 turns counterclockwise.

55 The frame 2 carries two upright posts 50 pro-

vided with vertically extending guide slots 52 of T-shape. Into these slots fit carriers 54. Mounted on these carriers are blocks 56, 58 having at their top keys 60, 61. These blocks carry rollers 62, 64, respectively, in the path of and engageable with the levers 32, 34. Springs 66 and 68 normally hold blocks 56, 58 and levers 32, 34 in raised position.

A spacing mechanism is formed by a lever 70 pivoted at 72. A link 74 pivoted to one end of this lever has at its end a pawl 76 engaging pinion 46. The movement of pawl 76 is limited by a pin and slot arrangement 78, and it is held against wheel 46 by a leaf spring 80. On the other end of lever 70 is pivoted a lever 82 movable from the dotted line position to the solid line position where it is held by a stop 84.

Mounted on blocks 56, 58 and on the frame are pairs of contacts 86, 88 connected to two electric buzzers 90, 92 of different tone by a suitable electric circuit.

This mechanism operates as follows:

When the dot key 60 is depressed, roller 62 engages lever 32 and moves it counterclockwise. Pawl 38 and ratchet 42 turn shaft 36 and drive roller 10, causing the tape to move forward one space. At the same time, printing rod 18 moves downwardly. Finally, rod 18 pushes the paper against die 14 and embosses a dot on the strip. As the rod 18 and lever 32 return upon release of the key, they have no effect on shaft 36 as pawl 38 runs idle.

If now dash key 61 is depressed, roller 64 engages lever 34 and moves rod 20 to emboss a dash on the tape, preferably transversely. When the key is released, it moves up and lever 34 turns counterclockwise, and through pawl 40 and ratchet 44 turns shaft 36 and feeds the paper forward.

It will thus be noted that after each operation the blank space for receiving the next impression is above the rear die, in this case the dash die. If a dot is to be formed, this blank space is fed forward before printing takes place into position over the dot die. For a dash, the space remains stationary until printing has taken place and is then fed forward.

It will also be noted that the plane joining the engaging points of the rollers which guide the tape is located above the tops of the dies. When feed roller 10 draws on the tape it thus pulls it up off the dies so that movement of the tape is not interfered with.

For spacing, the lever 82 is pushed to the right (Fig. 1) which through pawl 76 turns roller 10 to advance the tape by one space.

If a check is desired on the symbols, switch 94 may be closed and the operation of either key will produce an audible signal so that the user can detect an error in printing. This is also an aid to learning the code and especially to learning to read with the reading mechanism.

The reading mechanism for such a tape is shown in Figs. 7 to 9. The tape itself, shown in Fig. 5, in the preferred form has short symbols or dots and long symbols or dashes, the latter differing from the dots by their greater length transversely of the tape, but lying partly in the same longitudinal line. Fig. 6 shows an alternative form in which two dots transversely spaced are used instead of the dash.

The reading device has a frame 100. Feeding rollers 106 driven by a suitable motor 108 and guide rollers 110 serve for moving the tape through the machine from left to right in Fig. 8.

The tape is centered by further rollers 112 mounted to turn about vertical axes and is held flat to the platform by rollers 113 before passing under the feelers.

5 A shaft 114 is mounted above and transversely of the tape. On this are mounted single levers 116 and 118 and a double lever composed of two arms 120 on opposite sides of the single levers and a cross piece 122. The levers 116 and 118 have noses 124 and 126, respectively. Nose 124 is in the line common to the dots and dashes. Nose 126 is opposite the dashes only. Arms 120 have noses 128 which are clear of both the dots and dashes.

10 15 At its free end, lever 116 has a laterally extending contact arm 130 electrically connected to a buzzer 132. Arm 118 has a contact 134, connected to a battery 136, in the path of contact 130. Cross piece 122 carries a contact 138 in the path of contact 134 and connected to a second buzzer 140 of different tone.

20 25 The device operates as follows:

When a dot passes beneath the feeler mechanism, it engages the nose 124 and raises the free end of lever 116 until contact 130 engages contact 134 and energizes buzzer 132.

When a dash comes to the feelers, it engages both noses 124 and 126 and raises levers 116 and 118. Contact 134 engages contact 138 to sound 30 35 buzzer 140, while contact 130 closes no circuit because contact 134 has been moved from its normal position.

In making corrections, the tape is usually broken and repaired. If for this or for any other reason a crease occurs in the tape, it will engage all the noses and lift all the arms. This will move contact 134 out of reach of contact 130 and will also move contact 138 out of reach of contact 134, so that no signal will be given.

40 45 While I have described herein one embodiment of my invention, I wish it to be understood that I do not intend to limit myself thereby, except within the scope of the appended claims.

I claim:

1. A machine for embossing messages on a tape comprising a tape supplying device, dies located on one side of the tape path side by side in the direction of movement of the tape, embossing members mounted on the other side of the tape path for movement towards and from said dies, a shaft, levers pivotally mounted on said shaft and connected to said members, keys operatively connected to said levers to move the members towards the dies, means to move the members away from the dies, means connected to said shaft to feed the tape, and one-way means connecting each lever to the shaft whereby movement of one of said members towards embossing position feeds the tape in one direction while movement of the other member away from embossing position feeds the tape in the same direction, that member which actuates the last mentioned means being intermediate the other member and the tape supplying device.

2. A machine for embossing messages on a tape comprising a tape supplying device, means to guide the tape along a predetermined path, dies located on one side of the tape path side by side in the direction of movement of the tape embossing members mounted on the other side of the tape path for movement towards and from said dies, a shaft, levers pivotally mounted on the shaft and extending on opposite sides thereof, means connecting one lever to each of said members, keys operatively connected to said levers to

move the members towards the dies, means to move the members away from the dies, means connected to the shaft to feed the tape, ratchets on said shaft, and pawls carried by the levers engageable with said ratchets for connecting each lever to the shaft whereby movement of one of said members towards embossing position feeds the tape in one direction while movement of the other member away from embossing position feeds the tape in the same direction.

3. A machine for impressing messages on a tape comprising means to guide the tape, dies located on one side of the tape path side by side in the direction of movement of the tape, embossing members mounted on the other side of the tape path for movement towards and from said dies, a shaft, levers pivotally mounted on the shaft and extending on opposite sides thereof, means connecting one lever to each of said members, keys operatively connected to said levers to move the members towards the dies, means to move the members away from the dies, a feed roll engageable with the tape to feed the same, a gear rigid with said roll, a second gear secured on said shaft meshing with the first gear, ratchets on said shaft, and pawls carried by the levers engageable with said ratchets for connecting each lever to the shaft whereby movement of one of said members towards embossing position feeds the tape in one direction while movement of the other member away from embossing position feeds the tape in the same direction.

30

25

5

10

15

20

4. A machine for embossing messages on a tape comprising means to guide the tape, dies located on one side of the tape path side by side in the direction of movement of the tape, embossing members mounted on the other side of the tape path for movement towards and from said dies, a shaft, levers pivotally mounted on the shaft and extending on opposite sides thereof, means connecting one lever to each of said members, movably mounted keys, rollers carried by said keys engageable with said levers to move the same to move said members towards the dies, means to move the members away from the dies, a feed roll engageable with the tape to feed the same, a gear rigid with said roll, a second gear secured on said shaft meshing with the first gear, ratchets on said shaft, and pawls carried by the levers engageable with said ratchets for connecting each lever to the shaft whereby movement of one of said members towards embossing position feeds the tape in one direction while movement of the other member away from embossing position feeds the tape in the same direction.

5. In a device as claimed in claim 4, spacing means comprising a third pivoted manually operable lever, a third pawl engaging said second gear, and means connecting said third pawl to said third lever.

WALTER P. TAYLOR, JR.
